DIAMOND DRESSER ARM ASSEMBLY
Ottis R. Briney, Jr., Pontiac, Mich., assignor to Briney
Manufacturing Co., Pontiac, Mich., a corporation of
Michigan

Filed Oct. 22, 1962, Ser. No. 232,163
16 Claims. (Cl. 125—11)

The invention relates to material forming apparatus and refers more specifically to a dresser arm assembly for use in diamond dressing a grinding wheel or the like including a single or plurality of tool carrying heads adjustable from the end thereof opposite dressing tools carried thereby without being locked and unlocked.

In the past adjustment of individual tools carried by a dresser arm assembly has been a relatively tedious and inefficient task since with prior adjusting means locking and unlocking of each of the individual tool carrying heads thereof has been necessary in adjusting each individual tool. Locking and unlocking of the individual tool carrying heads is particularly undesirable since after an adjustment relocking of a tool carrying head often produces a substantial change in adjustment. In addition with prior constructions adjustment of the individual tool carrying heads has been accomplished from the end of the heads from which the tools extend which is undesirable since very little room is usually available at this end of the heads in the usual dresser arm assembly and installation.

It is therefore one of the objects of the present invention to provide an improved dresser arm assembly for use in dressing of grinding wheels and the like.

Another object is to provide an improved dresser arm assembly including a supporting frame having secured thereto a plurality of tool carrying heads adjustable from the ends thereof opposite that from which tools carried thereby extend.

Another object is to provide a dresser arm assembly as set forth above wherein the individual tool carrying heads are separately adjustable longitudinally of the arm assembly.

Another object is to provide a dresser arm assembly as set forth above wherein each of the tool carrying heads includes a substantially rectangular body member having a cylindrical opening therethrough, an eccentric cylindrical sleeve positioned within the opening having a radially outwardly extending flange at one end thereof engageable with the body member around one end of the opening to prevent passage of the sleeve through the opening, a bar holder extending through the sleeve having a radially extending flange on one end thereof engaged with the flange on the eccentric sleeve, an adjusting member positioned within the other end of the opening through the body member having a radially extending flange therearound operable to prevent the adjusting member from passing through the opening in the body member, resilient means extending between the adjusting member and bar holder to hold the bar holder, eccentric sleeve and adjusting member in assembly in the opening in the body member, means to prevent relative rotation between the bar holder and body member and means to provide rotation of said eccentric sleeve with said adjusting member.

Another object is to provide a tool carrying head including means for adjustably supporting a tool at one end thereof and means for adjusting the position of the tool carried at said one end thereof relative to an axis therethrough secured to the other end thereof.

Another object is to provide a tool carrying head including a body member having a cylindrical opening therethrough, an eccentric sleeve positioned within the cylindrical opening having a radially outwardly extending

2

flange at one end thereof operable to prevent the sleeve from passing through the opening, a bar holder positioned within the eccentric sleeve having a radially outwardly extending flange thereon engageable with the flange on the eccentric sleeve to prevent passage of the bar holder through the opening, a tool bar secured to the bar holder, an adjusting member positioned in the other end of the opening through the body member having a radially outwardly extending flange thereon for preventing passage of the adjusting member through the opening, resilient means operable between the adjusting member and bar holder for securing the adjusting member, bar holder and sleeve within the opening in the body member, a plurality of pre-stressed balls in cylindrical cages positioned between the bar holder and inner surface of the eccentric sleeve and between the outer surface of the eccentric sleeve and body member, means to prevent relative rotation between the body member and bar holder and for securing the adjusting member and eccentric sleeve together for simultaneous rotation.

Another object is to provide a dresser arm assembly which is simple in construction, economical to manufacture and efficient in use.

Other objects and features of the invention will become apparent as the description proceeds, especially when taken in conjunction with the accompanying drawings, illustrating a preferred embodiment of the invention, wherein:

FIGURE 1 is an elevation view of a dresser arm assembly constructed in accordance with the invention.

FIGURE 2 is a view of the dresser arm assembly illustrated in FIGURE 1 taken in the direction of the arrow 2 in FIGURE 1.

FIGURE 3 is a partial end view of the dresser arm assembly illustrated in FIGURE 1 taken in the direction of arrow 3 in FIGURE 1.

FIGURE 4 is an enlarged section view of the dresser arm illustrated in FIGURE 1 taken on the line 4—4 in FIGURE 1.

FIGURE 5 is a partial section view of the dresser arm illustrated in FIGURE 1 taken substantially on line 5—5 in FIGURE 4.

FIGURE 6 is a partial section view of the dresser arm illustrated in FIGURE 1 taken on line 6—6 in FIGURE 4.

With particular reference to the figures of the drawings one embodiment of the invention will now be considered in detail.

As shown best in FIGURE 1 the dresser arm 10 comprises an elongated supporting frame 12 to which a plurality of tool carrying head assemblies 14 are adjustably secured. The supporting frame 12, as shown in FIGURE 1, is pivotally mounted for arcuate movement in the direction of arrow 16 whereby the tools 20 may be moved into and out of dressing position with respect to the grinding wheel 22 to be dressed thereby.

The tool carrying head assemblies 14 are constructed so that the tool bars 24 may be adjusted transversely of the dresser arm assembly from the end 26 of the tool carrying head assemblies opposite the tool bars 24. In addition the tool carrying head assemblies are so constructed that it is not necessary to lock or unlock the assemblies before or after adjustment of the position of the tool bars has been accomplished. Adjustment of the tool bars is thus facilitated with the dresser arm assembly of the invention.

More specifically the supporting frame 12 includes a pair of elongated flat rectangular side plates 28 and 30 held in parallel spaced apart relation by spacing blocks 32 and 34 which spacing blocks are secured between the ends 36 and 38 of the side plates 28 and 30 by convenient means, such as welding or bolts.

As shown best in FIGURE 1 the sub-assembly consisting of the side plates 28 and 30 and spacing blocks 32 and 34 are secured to a supporting bracket 40 by means of bolts 42 extending through the openings 44 and 46 in the spacing block 32 and supporting bracket 40, respectively. An additional spacing block 48, as shown in FIGURE 1, may be provided between the supporting bracket 40 and spacing block 32 if desired. Bracket 40 is pivotally mounted to permit swinging of the supporting frame 12 in the direction of arrow 16 by convenient pivot support means (not shown).

The tool carrying head assemblies 14, as shown best in FIGURE 4, each include a generally rectangular body member 50, eccentric sleeve 52, bar holder 54 and bearing structures 56 and 58 separating the body member from the eccentric sleeve and the eccentric sleeve from the bar holder, respectively. The tool carrying head assemblies 14 are completed by the adjusting member 60 and the resilient means 62 acting between the bar holder 54 and adjusting member 60 to secure the body member, eccentric sleeve, bar holder and adjusting member in assembly.

Body member 50, as illustrated best in FIGURE 4 is generally rectangular and is provided with offset sides 64 to produce the abutments 66 whereby the body member fits between the side plates 28 and 30 of the supporting frame 12 and is supported for sliding movement on the surfaces 68 and 70 of the side plates.

Body member 50 of the head assemblies 14 is further provided with threaded openings 72 in the sides thereof for receiving bolts 74 therein which are operable to secure the head assemblies 14 in a longitudinally adjusted position on the supporting frame 12. Longitudinal adjustment of the tool carrying head assemblies 14 may be accomplished due to the elongated slots 76 provided in the side plates 28 and 30 through which the bolts 74 having washers 78 sleeved thereover extend.

Body member 50 is further provided with a cylindrical opening 80 extending therethrough, as shown best in FIGURE 4, in which the eccentric sleeve 52, bar holder 54 and bearing structures 56 and 58 are received. The longitudinally extending notch 82 provided in the end 84 of the opening 80 cooperates with the tongue portion 86 of the driving plate 88 to prevent relative rotation between the bar holder 54 and the body member 50, as will be considered in more detail subsequently.

Eccentric sleeve 52 is provided with the radially outwardly extending flange 90 at the end 92 thereof including the beveled abutment 94 thereon engageable with the mating beveled surface 96 at the end 98 of the opening 80 through the body member 50 to position the eccentric sleeve 52 axially within the opening 80. Eccentric sleeve 52 is provided with the longitudinally extending slot 100 therein in which the tongue portion 102 of the adjusting member 60 is positioned whereby rotation of the adjusting member 60 produces a similar rotation of the eccentric sleeve 52.

The eccentricity of the sleeve 52 is provided between the radially inner and outer cylindrical surfaces thereof. Thus on rotation of the eccentric sleeve 52 relative to the body member 50 and bar holder 54 movement of the bar holder 54 in the direction of arrow 104 in FIGURE 2 is accomplished to produce adjustment of dressing tool 20, as will be considered in more detail subsequently.

Bar holder 54 again, as shown best in FIGURE 4, comprises a solid cylindrical member 106 having a radially extending flange 108 at end 110 thereof and the beveled surface 112 thereon engaged with the beveled surface 114 on the sleeve 52 for axially positioning the bar holder 54 with respect to the eccentric sleeve 52. Drive plate 88 is secured to the end 116 of bar holder 54 by convenient means, such as the tongue 118 on the drive plate 88 and groove 120 in the bar holder 54 and bolts 122 extending through the drive plate 88 on both sides of the axis of generation of the cylindrical portion 106

of the bar holder and into the cylindrical portion 106 of the bar holder. Thus it will be seen that the drive plate 88 is rigidly secured to the bar holder 54 whereby with the tongue 86 of the bar holder 54 positioned in the notch 82 in the body member 50 the bar holder 54 is prevented from rotation relative to the body member.

The bearing assemblies 56 and 58 separating the body member 50 from the sleeve 52 and the sleeve 52 from the bar holder 54 each comprise a cylindrical sleeve or cage 124 having a plurality of openings 126 extending transversely therethrough in which the individual ball bearings 128 are held. The dimensions of the bearings, body member, sleeve and bar holder are such that the bearings are under a slight compressive force in assembly. Thus with the tool carrying head structure illustrated in FIGURE 4 it is not necessary to lock and unlock the adjusting member 60 between adjustments of the position of the tool bar 24 which is secured to the bar holder 54 for movement therewith on rotation of the eccentric sleeve with respect thereto.

As shown the tool bar 24 may be of different configuration depending on the grinding wheel 22 or other structure to be dressed with the tools 20 carried by the dresser arm assembly 10. Each of the tool bars 24 are secured to a bar holder 54 by means of a tongue 130 and groove 132 operable therebetween in cooperation with bolts 133. It will be noted that the tongue and groove operable between the tool bar and bar holder of each of the tool carrying head assemblies 14 are positioned eccentrically with respect to the axis of the opening through the body member and the axis of generation of the sleeve 52 and the axis of the bar holder 54. Thus dressing forces applied through the tools 20 to the tool bar 24 and bar holder 54 have less tendency to cause undesirable readjustment of the set position of a cutting tool 20 carried by the tool bar 24.

Adjusting member 60 again, as shown best in FIGURE 4, is a cylindrical member having an end portion 134 received within the end 136 of the opening 80 in the body member 50, an end 138 extending beyond the surface 140 of the body member 50 and a radially extending flange 142 positioned centrally thereof and engageable with the surface 140 of the body member 50. The outer periphery 144 of the flange 142 is calibrated, as illustrated best in FIGURE 3, and in conjunction with a calibration 146 on the body member provides an indication of the amount of adjustment of a tool 20 carried by a tool carrying head assembly 14 on relative rotation of the adjusting member 60 with respect to the body member 50.

Adjustment of the adjusting member 60 is accomplished by means of inserting an adjusting tool within the cylindrical openings 148 extending at right angles through the end 138 of the adjusting member 60 and turning the adjusting tool to produce rotation of the adjusting member. Adjustment of the position of the tool 20 may thus be accomplished from the end of the tool carrying head assembly 14 opposite the end thereof to which the tool 20 is secured, due to the rotation of the eccentric sleeve 52 with the adjusting member 60 in view of the slot 100 and tongue 102 connection therebetween.

The adjusting member 60 is further provided with the axially extending bore 150 having a large diameter portion 152 and a small diameter portion 154. The headed bolt 156 received in the large diameter portion 152 of the bore 150 and extending through the small diameter portion 154 thereof into a threaded opening 158 in the drive plate 88 and the resilient spring 160 operable between the bolt 156 and the adjusting member 60 provide the resilient means operable to hold the bar holder, eccentric sleeve, body member and adjusting member in assembly.

In over-all operation, when it is desired to dress the grinding wheel 22, the tool carrying head assemblies 14 which have previously been longitudinally positioned on the supporting frame 12 by means of the bolts 74 and

elongated slots 76 are adjusted transversely of the dresser arm assembly by rotating the adjusting members 60 on placing an adjusting tool in the cylindrical openings 148.

Rotation of an adjusting member 60 will produce corresponding rotation of the eccentric sleeve 52 due to the slot and tongue connection therebetween. Since the bar holder 54 is prevented from rotation relative to the body member 50 by the tongue 82 and notch 86 connection therebetween and the body member is held in a fixed position on the supporting frame 12 the bar holder 54 is caused to move transversely of the dresser arm assembly 10 in the direction of arrow 104 due to the relative eccentricity between the inner and outer cylindrical surfaces of the sleeve 52.

The tool bar 54 and therefore the cutting tool 20 connected to the bar holder 54 thus adjusted, are similarly adjusted to provide a desired location of the dressing tool 20 on pivoting of the dresser arm into dressing relation to the grinding wheel 22 or other device to be dressed. The dresser arm is then pivoted in a direction opposite the arrow 16 to move the dressing tool 20 into engagement with the structure to be dressed thereby.

Thus it will be seen that in accordance with the invention there is provided an improved dresser arm assembly wherein dressing tools may be adjusted without locking and unlocking the adjusting means therefor and without interference with the adjusting means by the dressing tools to be adjusted or the structure to be dressed.

While one embodiment of the invention has been considered in detail, other embodiments and modifications thereof are contemplated. It is therefore the intention to include all such embodiments and modifications as are defined by the appended claims within the scope of the invention.

What I claim as my invention is:

1. A dresser arm for use in dressing a grinding wheel or similar structure comprising an elongated supporting frame, a plurality of parallel extending tool carrying heads secured to the supporting frame in longitudinally spaced relation therealong, each of which heads includes a generally rectangular body member carried by the supporting frame and having a cylindrical opening therethrough, an eccentric sleeve positioned within the opening through the body member having a radially outwardly extending flange at one end thereof engageable with the body member around the periphery of the opening therethrough at one end thereof for preventing passage of the sleeve completely through the opening, a cylindrical bar holder inserted within said sleeve having a tool bar mounting flange extending radially outwardly at one end thereof engaged with the radially extending flange on the eccentric sleeve, a tool bar secured to said bar holder at said one end thereof, a cylindrical adjusting member inserted in the other end of the opening in the body member having a radially outwardly extending flange thereon engageable with the body member to prevent passage of the adjusting member through the opening in the body member, resilient means operable between the bar holder and adjusting member for securing the bar holder, eccentric sleeve and adjusting member within the opening in the body member, means operable between the eccentric sleeve and adjusting member for rotating the eccentric sleeve relative to the body member and bar holder in response to rotation of the adjusting member, and means operable between the bar holder and body member for preventing relative rotation between the bar holder and body member during rotation of said eccentric sleeve with respect thereto whereby the position of the tool bar may be adjusted with respect to the head on which it is mounted.

2. Structure as set forth in claim 1 wherein the means for preventing relative rotation between the bar holder and body member comprises an axially extending notch in the opening in the body member and a drive plate rigidly secured to the other end of the body member

having a tongue portion positioned within the notch in the body member.

3. Structure as set forth in claim 2 wherein the resilient means comprises an opening through the adjusting member, a threaded recess in the drive plate, a headed bolt passing through the opening in the adjusting member and secured in the threaded recess in the drive plate and a spring operable between the headed bolt and adjusting member urging the headed bolt and adjusting member in opposite directions.

4. Structure as set forth in claim 1 wherein the means for rotating the eccentric sleeve relative to the body member comprises an axially extending slot in the other end of the eccentric sleeve and an axially extending tongue on the adjusting member extending into said slot.

5. Structure as set forth in claim 1 wherein the adjusting member is provided with graduations around the radially extending flange and the body member is provided with a corresponding graduation therein and the adjusting member further includes a projection thereon having a plurality of transverse openings therethrough for the insertion of a tool therein for rotating the adjusting member.

6. An adjustable tool supporting head comprising a generally rectangular body member having a cylindrical opening therethrough, an eccentric sleeve positioned within the opening through the body member having a radially outwardly extending flange at one end thereof engageable with the body member around the periphery of the opening therethrough at one end thereof for preventing passage of the sleeve completely through the opening, a cylindrical bar holder inserted within said sleeve having a tool bar mounting flange extending radially outwardly at one end thereof engaged with the radially extending flange on the eccentric sleeve, a tool bar secured to said bar holder at said one end thereof, cylindrical cages having a plurality of ball bearings secured thereto inserted between the body member and sleeve and the sleeve and bar holder, a cylindrical adjusting member inserted in the other end of the opening in the body member having a radially outwardly extending flange thereon engageable with the body member to prevent passage of the adjusting member through the opening in the body member, resilient means operable between the bar holder and adjusting member for securing the bar holder, eccentric sleeve and adjusting member within the opening in the body member, means operable between the eccentric sleeve and adjusting member for rotating the eccentric sleeve relative to the body member and bar holder in response to rotation of the adjusting member and means operable between the bar holder and body member for preventing relative rotation between the bar holder and body member during rotation of said eccentric sleeve with respect thereto.

7. Structure as set forth in claim 6 wherein the means for preventing relative rotation between the bar holder and body member comprises an axially extending notch in the opening in the body member and a drive plate rigidly secured to the other end of the bar holder having a tongue portion positioned within the notch in the body member.

8. Structure as set forth in claim 7 wherein the resilient means comprises an opening through the adjusting member, a threaded recess in the drive plate, a headed bolt passing through the opening in the adjusting member and secured in the threaded recess in the drive plate and a spring operable between the headed bolt and adjusting member urging the headed bolt and adjusting member in opposite directions.

9. Structure as set forth in claim 6 wherein the means for rotating the eccentric sleeve relative to the body member and bar holder comprises an axially extending slot in the other end of the eccentric sleeve and an axially extending tongue on the adjusting member extending into said slot.

10. Structure as set forth in claim 6 wherein the adjusting member is provided with graduations around the radially extending flange and the body member is provided with a corresponding graduation thereon and the adjusting member further includes a projection thereon having a plurality of transverse openings therethrough for the insertion of a tool therein for rotating the adjusting member.

11. An adjustable tool supporting head comprising a body member having a cylindrical opening therethrough, an eccentric sleeve positioned within the opening through the body member having means at one end thereof for preventing passage of the sleeve completely through the opening, a cylindrical bar holder inserted within said sleeve, a tool bar secured to one end of said bar holder, an adjusting member inserted in the other end of the opening in the body member including means for preventing passage thereof through the opening in the body member, resilient means operable between the bar holder and adjusting member for securing the bar holder, eccentric sleeve and adjusting member within the opening in the body member, means operable between the eccentric sleeve and adjusting member for rotating the eccentric sleeve relative to the body member and bar holder in response to rotation of the adjusting member and means operable between the bar holder and body member for preventing relative rotation between the bar holder and body member during rotation of said eccentric sleeve with respect thereto.

12. Structure as set forth in claim 11 wherein the means for preventing relative rotation between the bar holder and body member comprises notch and tongue structure operable therebetween.

13. Structure as set forth in claim 11 wherein the resilient means comprises an opening through the adjusting member, a headed bolt passing through the opening in the adjusting member and secured to the bar holder and a spring operable between the headed bolt and adjusting member.

14. Structure as set forth in claim 11 wherein the means for rotating the eccentric sleeve relative to the body member and bar holder comprises tongue and slot means operable between the adjusting member and eccentric sleeve.

15. A dresser arm for use in dressing a grinding wheel or similar structure comprising a supporting frame including a pair of elongated parallel side members connected together at one end thereof and mounted for pivotal movement about said one end, a plurality of separate tool carrying heads secured to the supporting frame between said members in longitudinally spaced relation at the other end thereof, each of which heads includes a rectangular body member secured between the parallel side members having a cylindrical opening therethrough, an eccentric sleeve positioned within the opening through the body member having means at one end thereof for preventing passage of the sleeve completely through the opening, a cylindrical bar holder inserted within said sleeve including means for preventing passage of the bar holder to said sleeve, a tool bar secured to said bar holder

5 at one end thereof, an adjusting member inserted in the other end of the opening in the body member including means to prevent passage thereof through the opening in the body member, resilient means operable between the bar holder and adjusting member for securing the bar holder, eccentric sleeve and adjusting member within the opening in the body member, means operable between the eccentric sleeve and adjusting member for rotating the eccentric sleeve relative to the body member and bar holder in response to rotation of the adjusting member and means operable between the bar holder and body member for preventing relative rotation between the bar holder and body member during rotation of said eccentric sleeve with respect thereto.

10 16. A dresser arm for use in dressing a grinding wheel or similar structure comprising a supporting frame including a pair of elongated parallel side members connected together at one end thereof and mounted for pivotal movement about said one end, a plurality of separate tool carrying heads secured to the supporting frame between said members in longitudinally spaced relation at the other end thereof, each of which heads includes a rectangular body member secured between the parallel side members having a cylindrical opening therethrough, an eccentric sleeve positioned within the opening through the body member having means at one end thereof for preventing passage of the sleeve completely through the opening, a cylindrical bar holder inserted within said sleeve including means for preventing passage of the bar holder to said sleeve, a tool bar secured to said bar holder at one end thereof, an adjusting member inserted in the other end of the opening in the body member including means to prevent passage thereof through the opening in the body member, resilient means operable between the bar holder and adjusting member for securing the bar holder, eccentric sleeve and adjusting member within the opening in the body member, means operable between the eccentric sleeve and adjusting member for rotating the eccentric sleeve relative to the body member and bar holder in response to rotation of the adjusting member and means operable between the bar holder and body member for preventing relative rotation between the bar holder and body member during rotation of said eccentric sleeve with respect thereto.
